(57) **CLAIM**

The ornamental design for an order and signaling devices for low-voltage-switchgears, as shown and described herein.

DESCRIPTION

FIG. 1 is a front view of a first embodiment of an order and signaling devices for low-voltage-switchgears;

FIG. 2 is a rear view thereof;

FIG. 3 is a top view thereof;

FIG. 4 is a bottom view thereof;

FIG. 5 is a right side view thereof;

FIG. 6 is a left side view thereof; and

FIG. 7 is a perspective view thereof.

FIG. 8 is a front view of a second embodiment of an order and signaling devices for low-voltage-switchgears;

FIG. 9 is a rear view thereof;

FIG. 10 is a top view thereof;

FIG. 11 is a bottom view thereof;

FIG. 12 is a right side view thereof;

FIG. 13 is a left side view thereof; and,
